Specification for Design.

Patented Nov. 6, 1917.

Application filed February 5, 1915. Serial No. 6,390. Term of patent 7 years.

To all whom it may concern:

Be it known that I, WILLIAM H. McLAUGHLIN, a citizen of the United States, residing at Hartford, in the county of Hartford and State of Connecticut, have invented a new, original, and ornamental Design for Antiskid Devices, of which the following is a specification, reference being had to the accompanying drawings, forming part thereof.

In said drawings Figure 1 represent a

view in side elevation of an anti-skid device embodying the design which is the subject of this application and Fig. 2 represents a plan view of the same.

I claim:

The ornamental design for an antiskid device, as shown.

WILLIAM H. McLAUGHLIN.
